(No Model.)

W. C. TAUCKE.
CHEMICAL TELEGRAPH.

No. 256,253.

Patented Apr. 11, 1882.

UNITED STATES PATENT OFFICE.

WILHELM C. TAUCKE, OF NEW YORK, N. Y.

CHEMICAL TELEGRAPH.

SPECIFICATION forming part of Letters Patent No. 256,253, dated April 11, 1882.

Application filed August 20, 1881. (No model.)

To all whom it may concern:

Be it known that I, WILHELM C. TAUCKE, of the city, county, and State of New York, have invented certain new and useful Improvements in Electro-Chemical Telegraphs, of which the following is a specification.

This invention relates to improvements in electro-chemical or copying telegraphs, based on the principle of the well-known "Caselli-
Pan telegraph," but simplified in such a manner that not only common paper and ink, in place of metallic foil, may be used for writing the messages, but, furthermore, the construction essentially simplified without, however, impairing the synchronism of the instruments at the transmitting and receiving stations.

This invention embraces a rotary cylinder for the transmitting or receiving paper, a reciprocating stylus traversing the cylinder in line of its axis, and mechanism whereby a slow step-by-step motion is imparted to the cylinder and a rapid reciprocating motion to the stylus, the movements of the cylinder being intermittent between the strokes of the stylus. By this means a comparatively-rapid copying telegraph is produced. A conical pendulum is used for synchronizing the instruments at the transmitting and receiving stations.

In the accompanying drawings, Figure 1 represents a side elevation, partly in section, of my improved electro-chemical or copying telegraph. Fig. 2 is a plan view, partly in horizontal section, on line xx , Fig. 1. Figs. 3, 4, 5, and 6 are details of the apparatus, and Fig. 7 is a diagram showing the connection of the apparatus with the main battery and line.

Similar letters of reference indicate corresponding parts.

The shaft of the horizontal cylinder A is supported in suitable bearings of the frame of the apparatus. To the cylinder A an axial motion is imparted by means of finely-toothed gear-wheels a (millimeter-wheels) at both ends of the cylinder, which mesh with minutely-toothed pinions b , placed on a shaft that revolves in suitable bearings sidewise of or below the axis of the cylinder A. The shaft b' of the pinions b receives intermittent motion from a horizontal disk, d , having projecting teeth d' at diametrically-opposite points of the disk, said teeth

engaging a gear-wheel, b^2 , at the outer end of the pinion-shaft b' . The horizontal disk d is keyed to a vertical main shaft, e , which turns in a step and neck bearing of the frame of the apparatus. To the main shaft e continuous rotary motion is imparted by bevel-gear wheels operated by a drum, cord, and weight, said drum being wound up by means of a treadle, or by any other suitable means.

Above the horizontal cylinder A is arranged a point or stylus, B, the socket of which is guided in horizontal rails B' vertically above and parallel to the axis of the cylinder. The stylus B is kept by a spiral spring in contact with the surface of the cylinder and guided in a socket the shank of which is applied to a horizontal connecting-rod, B^2 , to which reciprocating motion is imparted either by a crank of the main shaft e , which crank is connected to the opposite end of the rod B^2 , as shown in Fig. 6, or by a disk, e^2 , which engages by a fixed stud, e^3 , a cross-shaped guide-piece e^4 of the rod B^2 , as shown in Figs. 1, 2, and 3.

For the purpose of keeping up the regular motion of the apparatus and preserving the synchronism of the apparatus at the transmitting and receiving stations, I preferably employ a regulating apparatus similar to that used in the Hughes type-printing telegraph. It consists of a weighted pendulum, f , which is suspended from a vertical standard, f' , and connected at its lower end by a pivot-link, f^2 , to a crank-arm, f^3 , of the main shaft e , the crank-arm being arranged above a horizontal fly-wheel. The pivot-link f^2 is pivoted to the outer end of the crank-arm f^3 , and connected thereto by a spring the tension of which is adjustable in any suitable manner. A brake-block, f^4 , at the outer end of the crank-arm f^3 is kept by the centrifugal motion of the pendulum in frictional contact with the circumferential flange of a fixed disk, f^5 , as shown in Figs. 1 and 4.

The adjustment of the weight in connection with the brake regulates the speed of the main shaft and keeps up the uniform motion of the cylinder and stylus at one station. The same regulating device at the other station imparts synchronous movement to the receiving cylinder and stylus. Each revolution of the main

shaft moves the cylinder for the distance of two teeth, and carries the stylus forward and back over the surface of the cylinder. The stylus B is lifted away from the cylinder when arriving at either end of its motion by a slight raise at each end of the guide-rails, as shown in Fig. 1.

For transmitting messages common paper may be used, upon which the message is written with any writing-ink, which, however, is preferably mixed with gum, dextrine, or other thickening substance to give it body. When common paper is used it has to be moistened when laying it on the cylinder, which, however, is not necessary when tin-foil is employed as the transmitting medium. The paper at the receiving-station may be in the shape of a continuous roll, which is prepared in the well-known manner with iodide of potassium and starch, the iodide of potassium appearing in bluish color by the influence of the electric current, so as to reproduce thereby the transmitted characters in the manner well known in chemical telegraphs.

If desired, the messages at the transmitting-station may also be connected and arranged on a roll, in which case it is to be guided to the cylinder by means of rollers to which a synchronous step-by-step motion is imparted. Whenever the stylus passes over the writing-ink the current is thrown into the line and a corresponding mark produced upon the paper at the receiving-station. As the stylus passes over the paper in one direction it intersects all the writing thereon. In its return motion it intersects the writing again, closely to its former path, owing to the light forward motion which the cylinder has received. The parallel intersecting of the message by the contact of the stylus is repeated until the stylus has passed over the whole message, which is simultaneously reproduced by the chemical action of the current on the paper at the receiving-station. I am aware that the mechanical means employed for operating the cylinder and stylus B, as well as the device for regulating the motion of the apparatus at the transmitting and receiving stations, are well known, and I therefore do not broadly claim the same.

The advantages of my apparatus consist, first, in the high speed of the same, as with each full revolution of the pendulum two motions of the stylus are produced; second, in the facility of keeping up the regular motion of the apparatus by the regulating-pendulum, so that the apparatus can be worked continuously for a considerable length of time without interruption; third, in the simplicity and cheapness of its construction, as compared to electro-chemical and type-printing telegraphs heretofore employed.

Having thus described my invention, I claim as new and desire to secure by Letters Patent—

1. The combination of a rapid reciprocatory stylus, a rotary cylinder, mechanism for imparting an intermittent motion to the cylinder between the strokes of the stylus, a motor, an intermediate vertical driving-shaft between the motor and cylinder, and a conical pendulum connected to the upper end of said vertical shaft, substantially as described. 65

2. The combination of a rotary cylinder, a rapid reciprocatory stylus, and means for raising the stylus out of contact with the cylinder at each end of its stroke, substantially as described. 75

3. The combination of a rotary cylinder, a rapid reciprocatory stylus, mechanism whereby the cylinder is rotated step by step between the strokes of the stylus, and means for raising the stylus out of contact with the cylinder at each end of its stroke, substantially as described. 80

4. The combination of the rotary cylinder A, gear a , shaft b' , pinion b , gear b^2 , disk d , with teeth d' , vertical shaft e , with balance-wheel and regulator, connecting-rod B², stylus B, and guide therefor, substantially as described. 85

In testimony that I claim the foregoing as my invention I have signed my name, in presence of two witnesses, this 8th day of August, 1881. 90

WILHELM CHR. TAUCKE.

Witnesses:

PAUL GOEPEL,
CARL KARP.
